T. W. SCHRAMM

POWDER PUFF

Filed Sept. 28, 1922

Inventor

Theodore W. Schramm

By

Frank C. Seaman.
Attorney

UNITED STATES PATENT OFFICE.

THEODORE W. SCHRAMM, OF BAY CITY, MICHIGAN.

POWDER PUFF.

Application filed September 28, 1922. Serial No. 591,190.

To all whom it may concern:

Be it known that I, THEODORE W. SCHRAMM, a citizen of the United States of America, and a resident of Bay City, in the county of Bay and State of Michigan, have invented certain new and useful Improvements in Powder Puffs, of which the following is a specification.

This invention relates to new and useful 10 improvements in powder puffs.

One object of the invention is to provide a powder puff having a small powder containing receptacle attached thereto, so that powder can be applied to the face of the 15 puff when desired.

Another object is to design a novel powder puff so constructed that the powder receptacle can be concealed within the puff when not in use, and is readily accessible for 20 the application of powder when desired.

A further object is to provide a convenient powder puff having a receptacle attached thereto, so that it will not be necessary to apply an excess quantity of powder 25 to the face of the puff for use when away from home, visiting, shopping or otherwise engaged.

A still further object is to design a powder puff with a receptacle attachment which 30 will in no manner interfere with the use of the puff, and which will eliminate the necessity of carrying a separate puff and powder receptacle.

With the above and other objects in view, 35 the present invention consists in the combination and arrangement of parts, herein-after more fully described, illustrated in the accompanying drawing, and particularly pointed out in the appended claims, it 40 being understood that changes may be made in the form, size, proportion, and minor details of construction, without departing from the spirit or sacrificing any of the advantages of the invention.

45 In the drawings:—

Fig. 1 is a top plan view of my improved powder puff illustrating the receptacle attached thereto, the dotted lines showing it concealed within the puff.

50 Fig. 2 is a side view thereof and illustrating the opening for inserting the receptacle.

Fig. 3 is a view of the receptacle proper, the dotted lines illustrating the cover in open position.

55 The conventional powder puff is formed

of a soft fluffy flexible material, and is a toilet article used by the feminine sex in general for applying powder to the face. These are made up in different shapes and styles, and are usually carried in the front 60 of the lady's waist or garment. Generally the wearer applies a quantity of powder to the face of the puff, for use when away from home folds it and then places it in the waist, and usually the puff unfolds, spilling the 65 powder which saturates the garments and is wasted, as well as inconveniencing the person when it is desired to apply the powder.

These disadvantages I have overcome by providing a small powder containing receptacle which is flexibly attached to and concealed within the puff proper. 70

Referring now particularly to the drawing, the numeral 5 indicates a conventional powder puff such as used by ladies in general, these are usually formed of a top and bottom piece of fabric or other material sewed together on the edges to form a flat round puff, and in my improved construction the puff proper is formed in an identically similar manner excepting that I provide an opening 6 in the edge which is adapted to be closed by means of a common snap attachment 7. A flexible ribbon or cord 8 is secured to the edge of the opening, the free end being secured to a small box or receptacle 9 which is provided with a cover 9^a hinged as shown at 10, and this cover can be provided with a snap locking attachment 85 to hold it in closed position and prevent the spilling of the powder when the receptacle is concealed within the puff. 90

The receptacle can of course be of any construction to suit the manufacturer, and the ribbon or cord can be attached in any 95 desired manner, also, the powder puff can be provided with a small pocket designed to accommodate the receptacle, and other minor changes may be resorted to without departing from the spirit of the invention. 100

From the foregoing description it will be obvious that I have perfected a very simple, and convenient combined powder puff and receptacle, whereby the powder may be conveniently boxed and concealed within the 105 puff.

What I claim is:—

1. A double faced flexible powder puff having a powder receptacle remote from the puff and flexibly secured thereto. 110

2. A powder puff having a flexible ribbon or cord secured thereto, and a powder receptacle attached to said cord or ribbon.
3. A powder puff having a flexible cord or ribbon secured thereto, a powder receptacle attached to the said cord, and an opening in the puff adapted to receive said receptacle when not in use.
4. A powder puff having a flexible cord

or ribbon secured thereto, a powder containing receptacle attached to said cord, an opening in the puff adapted to secure the receptacle when not in use, and means for closing said opening.

In testimony whereof I affix my signature.

THEODORE SCHKAMM.
